R. C. Powell,

Inventor:

Charles H. Redman,

By Straker Co. Atty's.

UNITED STATES PATENT OFFICE.

CHARLES H. REDMAN, OF NEWARK, NEW JERSEY.

PENCIL-SHARPENER.

SPECIFICATION forming part of Letters Patent No. 453,448, dated June 2, 1891.

Application filed January 29, 1891. Serial No. 379,508. (No model.)

To all whom it may concern:

Be it known that I, CHARLES H. REDMAN, a citizen of the United States, residing at Newark, in the county of Essex and State of New Jersey, have invented certain new and useful Improvements in Pencil-Sharpener; and I do hereby declare the following to be a full, clear, and exact description of the invention, such as will enable others skilled in the art to 5 know which it appertains to make and use the same, reference being had to the accompanying drawings, and to letters of reference marked thereon, which form a part of this specification.

15 This invention is to provide a device of greater convenience and to enable the pencil to be sharpened with greater facility and ease; and it consists in the improved pencil-sharpener and in the arrangements and combinations of parts, substantially as will be hereinafter set forth, and finally embodied in the clauses of the claim.

Referring to the accompanying drawings, in which like letters indicate corresponding parts in each of the figures, Figure 1 is a plan of the device and showing the pencil about to be inserted therein. Fig. 2 is a section taken on line *x*, and Fig. 3 a section taken on line *y*.

30 In said drawings, *a* indicates a metal casting, of which *d* is a finger-piece, *a*² a flat shank, *b* a conical sharpening-head, the axial center of which is at right angles to the longitudinal center of the shank and finger-piece, and *c* a cutter-seat in the longitudinal line of the shank, but on opposite sides of the conical head in which the pencil is inserted when being sharpened.

g indicates a blade arranged on the seat and 40 having its cutting-edge extend to a slot *g'* in the conical head, so as to cut and sharpen the pencil *h* when inserted and turned in said head. The blade is held on said seat by a set-screw *i*, which allows of an adjustment of 45 the blade with reference to the slot, and also allows of a removal of the blade for sharpening.

f indicates a flat file for sharpening the lead, soldered on the shank, the latter being 50 recessed, as shown, to receive the same. A

projecting stop *e* extends transversely across the shank to protect the fingers of the operator from the lead when filing the pencil to a point.

By holding the sharpener by the finger-piece in the position shown in Fig. 1 the wooden part of the pencil is first sharpened by the cutter, and then the lead, which is not allowed to engage the blade and dull the same, is filed to a point on the file of the shank. 55 The flat shank interposed between the finger-piece and the conical head provides a bearing for the flat file and enables the latter to be placed so that the cutting or lead-sharpening chisel-edges will lie parallel with the axial 60 center of the conical head. By this construction the person sharpening will not have to change the angle of the pencil when changing from the wood-sharpening to the lead-sharpening operations, as in cases where the file 70 is arranged directly on the side of the conical head.

Having thus described the invention, what I claim as new is—

1. The combination, with the finger-piece, 75 flat shank, and conical head having a slot and cutter, of a file arranged on said flat shank, the cutting-edges of which are parallel with the axial center of the said conical head, substantially as set forth.

2. In combination, a flat shank having a finger-piece at one end and a conical cutter-head at the other, disposed with its axial center at right angles to the said shank, and a file arranged on said shank, substantially as 85 set forth.

3. In combination, a shank having a file on the face thereof, a finger-piece at one end thereof, a stop or ridge formed between the said file and finger-piece, and a cutter-head 90 having a slot and blade arranged at the other end of said shank, substantially as set forth.

In testimony that I claim the foregoing I have hereunto set my hand this 27th day of January, 1891.

CHARLES H. REDMAN.
